UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET-HANDLING MECHANISM.

Application filed May 26, 1923. Serial No. 641,772.

To all whom it may concern:

Be it known that I, HOWARD M. BARBER, a citizen of the United States, and resident of Stonington, in the county of New London and State of Connecticut, have invented a new and useful Improvement in Sheet-Handling Mechanism, of which the following is a specification.

In fabric printing machines when the sheet is cut from the fabric that has been baled, the cut often comes so close to a crease or fold in the fabric that the front end of the sheet which overhangs the cylinder gripper recess will turn inwardly into the recess, frequently taking such a position that the delivery carrier grippers will fail to grasp the front end of the sheet but will close outside of the same, thereby permitting the sheet to drop off from the cylinder and be wasted instead of being carried out to the proper delivery point.

The object of my invention is to provide in sheet handling mechanism, means for preventing this inward turning of the advance end of the sheet on its cylinder, thereby ensuring the taking off of the sheet from the cylinder by the delivery carrier grippers.

A practical embodiment of my invention is represented in the accompanying drawings, in which—

Fig. 1 represents a detail plan of an impression cylinder with my invention applied thereto.

Fig. 2 represents a detail section taken in the plane of the line II—II of Fig. 1, the delivery carrier and its grippers being represented in dotted lines.

Fig. 3 represents a detail section taken in the plane of the line III—III of Fig. 2, showing one means for laterally adjusting the position of one of the supporting fingers for the front end of the sheet.

The impression cylinder is denoted by 1, the set of grippers by 2 and the gripper recess by 3. The tympan is denoted by 4, the tympan bar by 5 and the tympan nippers by 6.

The delivery carrier is denoted by 7 and its grippers by 8, which grippers are arranged to coact with the grippers 2 of the impression cylinder for taking the sheets therefrom in the usual manner.

The means which I have shown for supporting the overhanging front end of the

sheet is constructed, arranged and located 55 as follows:—

A series of fingers 9 are secured to the tympan bar 5 in any desired position along the same by providing the bar with an undercut longitudinal groove 10 in which a nut 11 is slidably mounted. A screw 12 serves to not only secure the inner end of the finger 9 to the nut, but also serves to clamp the parts to the tympan bar. Each of these fingers 9 is provided with a laterally turned outer end 13 which forms an extension of the surface of the cylinder over the gripper recess a sufficient distance to support the leading end of the sheet in proper position to be grasped by the grippers 8 of 70 the delivery carrier 7 for the proper transfer of the sheet from the impression cylinder to the delivery carrier, these fingers serving to prevent the free end of the sheet from turning inwardly into the cylinder 75 where it may be missed by the grippers of the delivery carrier.

It is evident that various changes may be resorted to in the construction, form and arrangement of the several parts without departing from the spirit and scope of my invention; hence I do not wish to be limited to the particular embodiment herein shown and described, but

What I claim is:—

1. Sheet handling mechanism including a cylinder, its gripper recess and grippers arranged to close on the surface of the cylinder, and a skeleton support for the overhanging front end of the sheet, to ensure 90 the proper taking off of the sheet from the cylinder.

2. Sheet handling mechanism including a cylinder, its gripper recess and grippers arranged to close on the surface of the cylinder, and a plurality of laterally adjustable fingers forming an extension of the surface of the cylinder for supporting the overhanging front end of the sheet, to ensure the proper taking off of the sheet from the 100 cylinder.

3. Sheet handling mechanism including a cylinder having a gripper recess, grippers arranged to close on the surface of the cylinder and a tympan nipper bar, and a plurality of fingers carried by the the bar with their ends forming an extension of the surface of the cylinder for supporting the over-

22
hanging front end of the sheet, to ensure the proper taking off of the sheet from the cylinder.

4. Sheet handling mechanism including a cylinder having a gripper recess, grippers arranged to close on the surface of the cylinder and a tympan nipper bar, and a plurality of fingers carried by and independently adjustable along the bar with their ends forming an extension of the surface of the cylinder for supporting the overhanging front end of the sheet, to ensure the proper taking off of the sheet from the cylinder.
5. Sheet handling mechanism including a cylinder having a gripper recess, grippers arranged to close on the surface of the cylinder and a tympan nipper bar, and a plurality of fingers carried by and independently adjustable along the bar with their ends forming an extension of the surface of the cylinder for supporting the overhanging front end of the sheet from the cylinder.

20

In testimony that I claim the foregoing as my invention I have signed my name this 24th day of May, 1923.

HOWARD M. BARBER.
